(57) **CLAIM**

The ornamental design for an automated analyzer as shown and described.

DESCRIPTION

FIG. 1 is a front, top and right side perspective view of an automated analyzer according to the design;

FIG. 2 is a front, top and right side perspective view showing the cover open state thereof;

FIG. 3 is a front view thereof;

FIG. 4 is a left side view thereof;

FIG. 5 is a right side view thereof;

FIG. 6 is a top view thereof;

FIG. 7 is a bottom view thereof;

FIG. 8 is a rear view thereof; and,

FIG. 9 is an enlarged end view taken along line 9-9 of FIG. 3.

The dashed broken lines in the drawings show portions of the automated analyzer that form no part of the claimed design. The dot-dash broken lines in the drawings indicate boundaries of the claimed subject matter that form no part of the claimed design.

1 Claim, 9 Drawing Sheets
